UNITED STATES PATENT OFFICE.

CHARLES E. NEEDHAM, OF ALLENTOWN, PENNSYLVANIA, ASSIGNOR TO BETHLEHEM FOUNDRY & MACHINE COMPANY, A CORPORATION OF PENNSYLVANIA.

GRINDING MILL.

Application filed February 3, 1925. Serial No. 6,520.

This invention relates to grinding or pulverizing mills and particularly to that type of mill wherein the material to be ground is crushed by rolls which are forced outwardly by centrifugal force against the inner face of an annular die. In the embodiment of my invention herein disclosed, the crushing rolls are hung from an overhead support which is rotated by a vertical shaft driven by overhead 5 gearing. The movable parts of the mill are carried by a frame which comprises two oppositely located interchangeable uprights or legs mounted on the base of the mill and connected at their tops by an overhead structure 10 which forms a bearing and support for the vertical shaft and for the operating gearing for said shaft.

One of the objects of my invention is to improve the construction of this supporting 20 frame in such a manner that it is better able to withstand the strains incident to the operation of the mill. It has been customary heretofore, in order to prevent vibration or lateral strains on the vertical shaft, to employ a hollow or quill shaft which is held against lateral displacement by a fixed member that extends upwardly into and bears against the inner surface of the hollow shaft. This construction is complicated and expensive and 25 the shaft, by being made hollow, is considerably weakened. By forming the overhead support for the shaft of extremely rigid and strong construction and by employing a lower bearing supported from the hollow of the 30 grinding chamber, I am able to employ a solid shaft which will be securely held against any injurious vibration.

A further object of my invention is to provide an improved supporting frame which 35 may be economically manufactured, readily assembled and adjusted to proper assembled relation. A further object is to provide a supporting frame which can be made in standard parts ready for shipment to place 40 of installation and which can be then assembled without further machining or otherwise altering the form of the parts.

The grinding mill herein disclosed is adapted 45 to be operated by a motor located at the side of the mill, this motor being connected to a driving shaft mounted in the overhead supporting frame. For convenience of arrangement, it is sometimes desirable to mount the driving shaft at one side of the mill and sometimes at the opposite side. In accord-

ance with my invention, the mill actuating gearing and its supporting structure is so designed that the same parts may be assembled differently and the actuating shaft positioned to extend in one direction or another as desired so that the driving motor may be located upon one or the other side of the mill. 60

A further object of the invention is to provide an improved means for lubricating the mill actuating gearing and also to provide an 65 improved means for lubricating the crushing roll bearings.

In mills of the type described, it is customary to employ plows which move in the grinding chamber beneath the grinding rolls and 70 serve to stir up the material to be ground and force it into the path of the grinding rolls. A further object of my invention is to provide an improved and simplified supporting structure for these plows. 75

A further object is to provide an improved mounting for the spindles which carry the grinding rolls.

A further object is to provide an improved means for supporting the crushing 80 rolls whereby the rolls may be removed and replaced without disturbing the bearings on which they are rotatably mounted.

While I have described various features 85 of my invention as applicable to a grinding mill, it will be obvious that certain of these features are of more general application.

Numerous other objects and advantages 90 will appear from the following description taken in connection with the accompanying drawing, wherein Fig. 1 is a front elevation, partly in section, of a grinding mill, showing one embodiment of my invention.

Fig. 2 is a vertical section, partly in elevation and partly broken away. 95

Fig. 3 is a side elevation of one of the cast metal uprights or legs forming a portion of the supporting frame for the moving parts of the mill.

Fig. 4 is a section taken on the line 4-4 100 of Fig. 3, looking in the direction of the arrows.

Fig. 5 is a section taken on the line 5-5 of Fig. 2.

Fig. 6 is a vertical section, partly in elevation, of a grinding roll and its spindle mounting. 105

Fig. 7 is a horizontal section taken on the line 7-7 of Fig. 6, looking in the direction of the arrows.

Fig. 8 is a bottom elevation of a grinding roll showing the means for securing the same to its support.

Fig. 9 is a section taken on the line 9—9 5 of Fig. 8, looking in the direction of the arrows.

Fig. 10 is a view similar to Fig. 1, but showing a modified form of overhead supporting structure.

10 Fig. 11 is a top plan of a portion of the housing and supporting structure for the mill actuating gearing as employed in the form of invention shown in Fig. 10.

15 Fig. 12 is a top plan of the supporting structure for the vertical actuating shaft for the form of invention shown in Fig. 10.

Fig. 13 is a side elevation of the structure shown in Fig. 12.

Referring more particularly to Fig. 2 of the drawing, the grinding chamber 20 is formed by a lower base casting 21, upper annular member 23 which is supported from the base 21 and connecting screen 24, the general arrangement of these parts being such as is customarily employed in grinding mills of the type disclosed. Suitably supported inside the base 21 is a fixed annular die 25 which is adapted to be engaged by grinding rolls 27 of which there are a plurality equally spaced. Grinding rolls 27 are rotatably mounted on spindles 28 which are swung in bearings 29 mounted upon a rotatable plate 30 which is carried by a vertical actuating shaft, 31. The plate 30 is formed with openings 40 adapted to receive material to be ground from a hopper 41 and deliver the same to the grinding chamber in front of the grinding rolls 27 through chutes 43. The shaft 31 is adapted to be rotated by gearing 34 which receives power from an outwardly extending shaft 22 connected to a motor not shown. Shafts 31 and 22 and gearing 34 are housed and supported in a frame 36 which comprises two uprights or legs 37 and an overhead connecting structure 38.

Referring more particularly to Figs. 3 and 4, each of the uprights 37 is formed of a casting having top and bottom portions 50 and 51 and a center and two side connecting portions 53 and 54 of the form shown. Strengthening ribs or flanges 55 extend upwardly from the bottom of the upright and are connected at the top and bottom by flanges 56 and 57. Each of the uprights 37 is rigidly mounted on and connected to the base 21, there being provided for this purpose segmental flanges or ribs 58, preferably formed integral with the base 21. The outer surface of each of the flanges 58 and the inner surface 60 of the bottom 51 of the uprights 37 are turned to cylindrical form so that the bottom 51 of the uprights will fit tightly against the flange 58. Securing bolts 60 pass through the bottom of the uprights 37 and through 65 the flange 58 and also through the flange 57

and into the base 21 for the purpose of securing these parts together. The upper face of the top portion 50 of the uprights is machined and the inner face 63 of each top portion 50 is machined so that these surfaces form a portion of a cylinder having as its axis the axis of the vertical driving shaft 31. The overhead connecting structure 38 comprises a beam 65 which is provided near its ends with depending flanges 66. The outer faces of the flanges 66 are turned to cylindrical form so as to fit the inner faces 63 at the top of the uprights 37 and the lower face of each end of the beam 65 beyond the flanges 66 is machined so as to fit the upper face of the uprights 37. Bolts 68 which pass through the upper portion of the uprights 37 and through the beam and flanges 66 serve to secure the beam to the uprights 37.

In constructions of this character heretofore employed, it has been the practice to form each of the uprights 37 of a plurality of fabricated rolled steel members which were secured in an assembled relation when the mill was installed. Considerable difficulty was experienced in fitting the fabricated rolled steel members or other parts of the uprights together and a considerable amount of machining, cutting and drilling was necessary in the installing process. By forming the uprights 37 of a single casting and machining the parts in the manner described, I provide a unitary construction and there is thus no necessity of further machining or altering the form of the parts when the mill is installed. By making the legs, bases and beams of standard sizes and form, the substitution of parts for those which are worn or injured is greatly facilitated. By joining the beam 65 with the legs 37 along the flat top surface of the legs and the cylindrical surface 63, it is possible to mount the beam 65 with the driving shaft 22 extending toward the left as shown in Fig. 1, or if desired, the beam and parts carried thereby may be secured to the uprights with the shaft extending toward the right, that is, the beam and its connected parts turned through an angle of 180° and the end of the beam which is now connected to the left hand upright 110 would be connected to the right hand upright and vice versa. In this manner the position of the driving motor relative to the feeding mechanism which supplies the hopper 41 may be altered so that the feeding mechanism is positioned at the right or at the left of the driving means.

The beam 65 is formed with a central portion 71 having an opening for the reception of the shaft 31. Keyed to the upper end of the shaft 31 is a bevel gear 73 which is supported upon a thrust roller bearing 75 contained in an enlargement 76 of the central portion 71 of the beam 65. The extreme upper end of the shaft 31 is screw threaded at 125

- 78 and receives a nut 79 which bears on the upper end of the hub 80 of gear 73. From this construction it will be seen that the weight of the shaft 31 is sustained by the bearing 75 through the hub 80 of the gear 73. The enlarged portion 76 is formed with an outwardly extending flange 82 which carries the gear casing or pan 83 formed of a lower portion 85 and an upper portion or top 86 bolted to the lower portion. The beam 65 at the left of its central portion, as shown in Fig. 1, is formed with a recess 90 which extends along the length of the beam which recess is formed with a central depression 91. The actuating shaft 22 extends into the recess 90 and is journaled in a roller bearing 95 located at the inner side of the depression 91 and a roller bearing 96 at the outer side of the depression 91. A bevel pinion 98 is keyed to the shaft 22 between the bearings 95 and 96 and is adapted to mesh with and operate the bevel gear 73. Between the bearing 96 and the pinion 98 is a plate 100 which is rigidly secured in the recess 90 and between the plate 100 and the pinion 98 is a thrust bearing 101. The plate 100 serves the purpose of receiving the thrust of the thrust bearing 101 and also acts as a partition to prevent oil in the bearing 96 from flowing directly into the depression 91 of the recess 90 in a manner more fully to be described hereafter. The top of the plate 100 is formed with an opening or channel 103, which forms a communication between the bearing 96 and the space surrounding the pinion 98. To the rear of the bearing 96, the recess 90 forms a chamber 105 which chamber is in communication with the depression 91 by means of a passage 106. Oil in the chamber 105 is prevented from flowing outwardly along the shaft 22 by means of a labyrinth seal 107 and a packing gland 108. The upper inner wall of the casing or pan 83 immediately above the pinion 98 is inclined as shown in Fig. 1 and terminates at its lower end at a point 110 which lies immediately above the opening 103.
- In practice, oil is introduced through an opening 112 in the top of the gear housing above bearing 96 and flows downwardly into the depression 91 where it assumes a level indicated roughly by a dotted line in Fig. 1. As the pinion 98 is rotated, a part of this oil will be carried or thrown upward against the bevel gear 73 and against the top of the pan 83. A part of this oil will flow down the inclined inner face of the pan to the point 110 and will then drop off into the opening 103 from whence it will flow to the bearing 96 and lubricate the same. This oil will return to the depression or oil sump 91 through the passage 106 which leads from the chamber 105 to the sump. In this manner, it will be seen that a constant circulation of oil is maintained to and from the bearing 96 and at the same time the natural level of the oil in the recess 90 will be sufficiently low so that there will be no tendency of the oil to flow out through the gland 108. There is no opening through which oil in the recess 90 at the rear of bearing 95 may escape and this bearing 70 which receives a sufficient amount of oil from the splash of the pinion 98 will be well lubricated. For the purpose of directing a portion of the oil splashed up by the pinion 98 to the bearing 95, a baffle 99 may be provided, located above the bearing 95.
- In the form of invention disclosed, I have shown a split bearing member 115 secured by bolts on the base 21 in which the lower end of the shaft 31 rotates. The bearing 115 acts 80 as bracing means for the lower end of the shaft 31 but does not sustain the weight of the shaft, this weight being sustained entirely by the upper bearing 75.
- The plate 30 is circular in form and extends outwardly to within a short distance of the annular member 23 so as to prevent dust from the grinding chamber 20 getting into the bearings above the plate 30. The plate 30 is provided with radially extending openings or slots 116 through which extend the roll carrying spindles 28. The upper portion of each of the spindles 28 is tapered at 117 and is adapted to be firmly secured within a tapered opening 117' in a rocker head 118 by means of a nut 119 which engages the screw threaded end 120 of the spindle 28. The rocker head 118 has, preferably cast integral therewith, a portion 122 which forms at its outer ends the trunnions 123. Trunnions 123 are supported in the bearings 29, bolted to the plate 30, one at each side of the slot 116. The trunnions 123 are preferably formed with removable steel facings or sleeves 126 which bear on the brass linings 127 of the bearings 29. By forming the trunnions 123 integral with the rocker head, an exceedingly strong and simple construction is provided and little or no difficulty is experienced in making and maintaining the parts 100 tight. Plates 121 and 124 are secured to the top of the supporting plate 30 and serve as closures for the portions of the openings 116 which are not closed by the rocker head 118.
- Rotatably supported on the spindle 28 is 115 a hollow member 130 which comprises a member 131 carrying the crushing roll 27 and a sleeve or annular member 132 which is rigidly secured to the roll-supporting member 131 by bolts 134. The spindle 28 is 120 formed with an enlargement or flange 135, forming a shoulder which carries the weight of the crushing roll and member 130 through a roller or other thrust bearing 137. Between the sides of the lower end 140 of the spindle 125 28 and the side inner wall of the roll-supporting member 131 are roller bearings 141. Fixed to the interior of the member 131 is a bearing plate 144 which is adapted to rotate against a thrust button 145 secured to the 130

lower end of the spindle 28. The inner wall of the sleeve member 132 above the thrust bearing 137 is tapered upwardly to a point 147 close to the spindle 28 so as to form an oil chamber 148. Above the point 147 the interior of the sleeve member 132 expands to form an oil chamber 150. In the upper portion of the chamber 150 and between the sleeve member 132 and the spindle 28 is located the roller bearing 151. Seated in the chamber 150 above the bearing 151 and secured to the sleeve member 132 is an annular member 153 which is spaced from the spindle 28 at its lower end, but is in contact therewith at its upper portion. The upper ends of the annular member 153 and the sleeve member 132 and the lower face of the rocker head 118 form a labyrinth 160 to prevent the escape of oil outwardly from the chamber 150. Oil is supplied to the spindle bearings through a vertical passage 162 which is normally closed at its top by a plug 163 and communicates at its lower end through an opening 164 in the thrust button 145 to the space between the thrust button and the plate 144.

The oil which is supplied to the passage 162 passes between the thrust button 145 and the plate 144, thence upwardly through the bearing 141, around the outer edge of the enlargement 135 of the spindle 28, through the thrust bearing 137 upward through tapered chamber 148 into the chamber 150 where it comes in contact with and lubricates the bearing 151. By forming the chamber 148 with an upward taper as shown, or with a contracted upper portion, oil introduced into the passage 162 remains in contact with the bearings 141 and 137 during operation of the machine. If the outer wall of the chamber 148 were vertical instead of inclined as shown, the centrifugal force due to the rotation of the member 130 would cause the oil in the chamber 148 to rise along its outer wall with the result that it would be thrown out at the top of the member 132 and the lower spindle bearings would quickly become dry. By forming the chambers 148 and 150 in the form shown, the oil is merely forced against the outer wall of the chamber and the tendency to rise in and flow out of the chambers, due to centrifugal force, is counteracted. It will of course be understood that sufficient oil is introduced into the passage 162 to cause the oil to rise into the chamber 150.

The roll 27 is formed with a tapered opening 170 adapted to receive the tapered portion 171 of the member 131. The tapered portion of 171 carries an outwardly projecting pin 175 which is seated in a slot 176 in the inner portion of roll 27 to prevent rotation of the roll 27 on the member 131. The roll-carrying member 131 is screw threaded at 173 at its lower end and is adapted to receive a nut 174. The nut 174 is provided with a plurality of openings 178, the lower

portions of which are circular in cross section and the upper portions square in cross section and tapered as shown in Figs. 8 and 9. Each of these openings is adapted to receive a jack screw 180. The jack screw 70 is formed at its outer end with a squared head 181, an intermediate screw threaded portion 182 and at its inner end with a flanged head 183 adapted to bear against the roll 27. Between the threaded portion 182 of the jack screw 180 and the tapered walls of the opening 178 is a split locking sleeve 185 which is screw threaded on its inner surface and has an inclined outer surface adapted to engage the tapered surface of the opening 182. 80

In order to secure the roller on the member 131, it is placed over and tapered portion 171 and the nut 174 screwed on by hand. The jack screws 180 are then tightened in succession with the result that the pressure heads 85 183 force the roll 27 tightly against the outer tapered surface of the portion 171. The sleeve 185 by this operation is forced back into the tapered recess thereby locking the screw 180. In this manner, the roll 27 is securely fastened to the member 131 and there is practically no danger of the screws 180 or of the roll 27 working loose during the operation of the mill. It will be noted that the roll 27 is removable and may be renewed without disturbing or necessitating the renewal of its bearing support. When a roll becomes worn and requires replacement, it is generally merely necessary to replace the roll itself as all other parts may be used with the new roll. The flanged head 183 is formed of larger diameter than the opening in the sleeve 185 so that in case the screw 180 should happen to become loose, there is no danger of its falling out of the opening 178. 100

The plate 30 is extended at the openings 40 to form tubular supporting portions 190 for the chutes 43, the chutes 43 being secured in the tubular portions 190 by a bayonet joint indicated at 192 and by a semi-cylindrical strap 193 which is secured by bolts 194 to a shoulder which may be regarded as formed by cutting away a portion of the end of the extension 190. Plow bars 195 are secured to the extensions 190 by means of bolts 196 and 115 straps 197 and are adapted to carry the plows 198 which move through the mass of unground material lying at the bottom of the grinding chamber and force the same upwardly into the path of the grinding rolls 27. 120

In Figs. 10-13 inclusive, I have shown a modified mounting for the movable parts of the mill. Instead of mounting the vertical shaft 31 and the gearing 34 on a single beam as is shown in Figs. 1 and 2, I provide 125 one mounting for the shaft 31 and gear 73 and a separate mounting for the shaft 22, pinion 98 and the gear housing. For this purpose, I provide two supporting members 200 and 201, each of which is adapted to be independ- 130

ently supported at its ends by the uprights 37. The member 201 which forms the gear housing, instead of being bolted to an overhead beam as shown at 82 in Fig. 1, is supported directly on the uprights 37, being secured at one of the uprights at 203 and on the other upright by means of a leg 204 which is carried by the pan 205. The member 200 which forms the supporting beam for the vertical shaft 31 and the parts carried thereby is formed at one end with spaced projections 206, which are secured to one of the uprights 37 and embrace the lower end of the leg 204. At its opposite end, the member 200 is bifurcated to form arms 208 which surround the recessed portion 209 of the member 201 and terminate in supporting end portions 210 which rest upon and are secured to the other upright 37. The members 200 and 201 are separately and independently supported and may be adjusted in position relative to one another, as for example, by inserting shims between the tops of the uprights 37 and one or other of the members. This is advantageous in order to secure the proper meshing of the pinion 98 with the gear 73. The members 200 and 201 also have an advantage over the beam 65 as shown in Fig. 1 in that they are of simpler and cheaper construction than the beam 65.

I claim:

1. In a centrifugal grinding mill having a grinding chamber, a base formed with an up-standing surface turned concentric with the vertical centre axis of said grinding chamber, grinding rolls movable in said chamber, a vertical shaft for moving said rolls, gearing for actuating said shaft and a supporting frame comprising two uprights, each formed of a heavy casting mounted on said base, said castings expanding peripherally toward said base and being formed with turned surfaces complementary to and fitting the turned surfaces on said base, said castings being formed with machined upper surfaces and an overhead casting mounted on said uprights and having supporting bearings for said shaft and gearing, and being formed with machined surfaces which fit the machined surfaces of said uprights.

2. In a centrifugal grinding mill having a grinding chamber, grinding rolls movable in said chamber, a vertical shaft for moving said rolls, a base casting formed on its upper face with ribs located at opposite sides of said grinding chamber, each of said ribs having an approximately cylindrical side surface, two uprights supported on said base, each formed of a casting having an approximately cylindrical surface adapted to fit the surface of said ribs, and an overhead structure secured to the top of said uprights and forming a supporting bearing for said vertical shaft.

3. In a centrifugal grinding mill having a grinding chamber, grinding rolls movable

in said chamber, a vertical shaft for moving said rolls, a base casting formed on its upper face with ribs located at opposite sides of said grinding chamber, each of said ribs having an approximately cylindrical side surface, 70 two interchangeable uprights supported on said base, each formed of a casting having an approximately cylindrical surface adapted to fit the surface of said ribs, and an overhead structure secured to the top of said uprights 75 and forming a supporting bearing for said vertical shaft.

4. In a centrifugal grinding mill having a grinding chamber, grinding rolls movable in said chamber, a vertical shaft for moving said rolls, a base casting, interchangeable uprights secured to said base on opposite sides of said grinding chamber, and an overhead structure forming a supporting bearing for said shaft, 80 said structure being supporter on said uprights in one position and being adapted to be supported on said uprights in a reverse position.

5. In a centrifugal grinding mill having a grinding chamber, grinding rolls movable in 90 said chamber, a vertical shaft for moving said rolls, a base casting, interchangeable uprights, each formed of a single casting, secured to said base on opposite sides of said grinding chamber, and an overhead structure forming 95 a supporting bearing for said shaft, said structure being supported on said uprights in one position and being adapted when disconnected from said uprights to be rotated horizontally through 180° without removing 100 said uprights, grinding rolls and vertical shaft and to be supported on said uprights in a reverse position.

6. In a centrifugal grinding mill having a grinding chamber, grinding rolls movable in 105 said chamber, a vertical shaft for moving said rolls, said shaft being adapted to sustain the weight of said rolls, a base casting formed with ribs at opposite sides of said grinding chamber, two uprights each formed 110 of a single heavy casting resting on said base and secured to said ribs, said last named castings being formed with a flat top and an approximately cylindrical upper side surface, and an overhead structure on said uprights, 115 said structure forming a supporting bearing for said shaft and formed at its ends with flat and cylindrical surfaces adapted to fit and to be secured to the flat and cylindrical surfaces respectively of said uprights, the parts being formed so that said structure may be reversed in position on said uprights.

7. In a grinding mill, a grinding chamber, feeding means at one side of said chamber for delivering material thereto, grinding elements movable in said chamber, a vertical shaft for moving said elements, gearing for operating said shaft, a base, uprights, each formed of a casting secured to said base, an overhead structure forming supporting bearings for said 125 130

- shaft and gearing, an actuating shaft extending along said structure to a point at one side of said feeding means, said overhead structure being carried by said uprights and adapted 5 to be secured thereto in a position such that said actuating shaft lies at one side of said feeding means or in a position such that the said actuating shaft lies at the other side of said feeding means.
- 10 8. In a centrifugal grinding mill having a grinding chamber, grinding rolls movable in said chamber, a vertical shaft for moving said rolls, gearing for actuating said shaft, a base, uprights, each formed of a casting mounted on 15 said base at opposite sides of said grinding chamber, an overhead beam supported on said uprights and forming a supporting bearing for said shaft and a housing for said gearing supported on said uprights.
- 15 9. In a centrifugal grinding mill having a grinding chamber, grinding rolls movable in said chamber, a vertical shaft for moving said rolls, gearing for actuating said shaft, a base, uprights, each formed of a casting mounted 20 on said base at opposite sides of said grinding chamber, an overhead beam supported on said uprights and forming a supporting bearing for said shaft and a housing for said gearing supported on said uprights, said housing 25 being separated from said beam.
- 10 10. In a centrifugal grinding mill having a grinding chamber, grinding rolls movable in said chamber, a vertical shaft for moving said rolls, gearing for actuating said shaft, a 30 base, uprights, each formed of a casting mounted on said base at opposite sides of said grinding chamber, a housing for said gearing supported at its ends on said uprights, and a beam formed with bifurcated ends embracing 35 the ends of said housing and secured to said uprights.
- 11 11. In a centrifugal grinding mill having a grinding chamber, grinding rolls movable in said chamber, a vertical shaft for moving said rolls, gearing for actuating said shaft, a 40 base, uprights, each formed of a casting mounted on said base at opposite sides of said grinding chamber, a housing for said gearing supported at its ends on said uprights, and a beam formed with bifurcated ends embracing 45 the ends of said housing and secured to said uprights.
- 15 12. In a centrifugal grinding mill having a grinding chamber, grinding rolls movable in said chamber, a vertical shaft for moving said rolls, gearing for actuating said shaft, a base, supporting means mounted on said base, 50 an overhead beam supported on said means and forming a supporting bearing for said shaft, and a housing for said gearing supported on said means, said housing being 55 separate from said beam.
- 15 13. In a centrifugal grinding mill having a grinding chamber, grinding rolls movable in said chamber, a vertical shaft for moving said rolls, a bevel gear on said shaft, a bevel pinion meshing with said gear, a laterally extending shaft on which said pinion is mounted, 70 a base, uprights mounted on said base on opposite sides of said grinding chamber, a housing supported at its ends on said uprights and formed with a recessed portion adapted to enclose said pinion, and a beam 75 supported on said uprights and formed with bifurcated ends embracing said recessed portions.
14. In a centrifugal grinding mill having a grinding chamber, grinding rolls movable in said chamber, a vertical shaft for moving said rolls, a bevel gear on said shaft, a bevel pinion meshing with said gear, a laterally extending shaft on which said pinion is mounted, 80 a base, uprights mounted on said base on opposite sides of said grinding chamber, a housing supported at its ends on said uprights and formed with a recessed portion adapted to enclose said pinion, bearings on said housing for said laterally extending shaft, said 85 recessed portion forming an oil for lubricating said pinion and bearings, and a beam mounted on said uprights independently of said housing and formed with a bifurcated end embracing said recessed portion. 90
15. In a centrifugal grinding mill having a grinding chamber, grinding rolls movable in said chamber, a vertical shaft for moving said rolls, a bevel gear on said shaft, a bevel pinion meshing with said gear, a laterally extending shaft on which said pinion is mounted, 95 a gear housing formed with an oil well in which said pinion rotates, bearings in said housing for said laterally extending shaft, and means whereby the rotation of said 100 pinion supplies oil to said bearings.
16. In a centrifugal grinding mill having a chamber, grinding rolls movable in said chamber, a vertical shaft for moving said rolls, a bevel gear on said shaft, a bevel 110 pinion meshing with said gear, a laterally extending shaft on which said pinion is mounted, a gear housing formed with a well adapted to contain oil in which said pinion dips, bearings for said laterally extending shaft 115 in said housing above said well, and means whereby oil raised by the rotation of said pinion is supplied to said bearings.
17. In a centrifugal grinding mill having a grinding chamber, grinding rolls movable in said chamber, a vertical shaft for moving said rolls, a bevel gear on said shaft, a bevel 120 pinion meshing with said gear, a laterally extending shaft on which said pinion is mounted, a gear housing formed with a well adapted 125 to contain oil in which said pinion dips, a bearing for said laterally extending shaft in said housing above said well, the top of said housing above said pinion being inclined 130 towards said bearing so that oil raised by 135

- rotation of said pinion will be supplied to said bearing.
18. In a grinding mill, movable grinding elements, a vertical shaft for moving said elements, a bevel gear on said shaft, a bevel pinion below said gear and meshing therewith, a horizontal shaft upon which said pinion is mounted, bearings for said shaft on the outer side of said pinion, a gear housing formed with a recessed portion adapted to contain said pinion and bearings, said recessed portion being formed with a depression adapted to contain oil in which said pinion dips, a partition between said bearing and pinion and formed with an opening in its upper portion, said housing being formed with an inner passage extending beneath said bearing and partition and the top of said housing above said pinion being inclined downwardly toward said opening whereby oil in said depression, by the rotation of said pinion, is splashed up onto the inclined top of said housing, flows down into said opening to said bearing, thence through said bearing and said passage back to said depression.
19. In a grinding mill, movable grinding elements, a vertical shaft for moving said elements, a bevel gear on said shaft, a bevel pinion below said gear and meshing therewith, a horizontal shaft upon which said pinion is mounted, a bearing for said shaft, a gear housing formed with a recessed portion adapted to contain said pinion and bearing, said recessed portion being formed with a depression adapted to contain oil in which said pinion dips, a partition between said bearing and pinion, the top of said housing above said pinion being inclined outwardly and said parts being formed with upper and lower passages leading to said bearing whereby oil in said depression, by the rotation of said pinion, is splashed up onto the inclined top of said housing, flows down into the said upper passage to said bearing and back to said depression through said lower passage.
20. In a centrifugal grinding mill having a grinding chamber, grinding rolls movable in said chamber, means for moving said rolls comprising a bevel pinion and a shaft on which said pinion is mounted, an overhead beam formed with a single recess extending along its length, said recess being formed with a depression adapted to contain oil in which said pinion dips, bearings for said shaft in said recess on opposite sides of said depression, and means whereby oil splashed up by the rotation of said pinion lubricates said bearings and is returned to said depression.
21. In a centrifugal grinding mill having a grinding chamber, grinding rolls movable in said chamber, means for moving said rolls comprising a bevel pinion and a shaft on which said pinion is mounted, an overhead beam formed with a single recess extending
- along its length, said recess being formed with a depression adapted to contain oil in which said pinion dips, bearings for said shaft in said recess on opposite sides of said depression, means whereby oil splashed up by the rotation of said pinion lubricates said bearings and is returned to said depression, and a seal surrounding said shaft at the outer end of said recess.
22. In a centrifugal grinding mill, a rotary support, depending spindles mounted eccentrically on said support, each of said spindles being formed with a supporting shoulder, an annular member rotatably mounted on said supporting shoulder and formed at its lower end and at said shoulder with an outwardly extending flange, a member rigidly secured to said flange and enclosing the lower end of said spindle, side roller bearings between said spindle and last named member and between said shoulder and annular member, and a grinding roll rigidly and removably secured to said last named member.
23. In a centrifugal grinding mill, a rotary support, spindles hung eccentrically from said support, each of said spindles being formed with a supporting shoulder, an annular member rotatably mounted on said supporting shoulder, and formed at its lower end and at said shoulder with an outwardly extending flange, a roll-supporting member rigidly secured to said flange, said annular and roll-supporting members enclosing the lower end of said spindle, said roller bearings between said spindle and roll-supporting member below said shoulder and between said spindle and annular member above said shoulder, and a grinding roll rigidly and removably secured to said roll-supporting member.
24. In a centrifugal grinding mill, a grinding roll formed with a tapered opening, a rotary support therefor formed with a tapered portion adapted to be received in the tapered opening of said grinding roll, securing means on the end of said tapered portion, jack screws passing through said means and adapted to engage said grinding roll to force the same onto the tapered portion of said rotary support.
25. In a centrifugal grinding mill, a grinding roll formed with a tapered opening, a rotary support therefor formed with a tapered portion adapted to be received in the tapered opening of said grinding roll, the end of said support being screw threaded, a nut adapted to engage said screw threaded portion and jack screws passing through said nut and adapted to engage said grinding roll to force the same onto the tapered portion of said support.
26. In a centrifugal grinding machine, a grinding roll having a tapered opening, a supporting member formed with a tapered

portion adapted to be received in said tapered opening and with a screw threaded end, a nut on said end formed with tapered openings having an angular cross section, jack screws passing through said openings and locking sleeves between said screws and the tapered sides of said openings, said jack screws being adapted to force said grinding roll into rigid engagement with the tapered portion of said supporting means.

27. In a centrifugal grinding mill having a grinding chamber, grinding rolls movable in said chamber, means for moving said rolls comprising a bevel pinion and a shaft on

which said pinion is mounted, an overhead beam formed with a single recess extending along its length, said recess being formed with a depression adapted to contain oil in which said pinion dips, bearings for said shaft in said recess on opposite sides of said depression, and means whereby oil is splashed up by the rotation of said pinion, lubricates said bearings and is returned to said depression, said means comprising members located above said shaft for directing oil splashed up by the pinion, laterally toward said bearings.

CHARLES E. NEEDHAM.
